(57) CLAIM

The ornamental design for an automobile, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front elevational view of an automobile, showing our new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a front and left side perspective view thereof;

FIG. 7 is a front and right side perspective view thereof;

FIG. 8 is a top, rear and left side perspective view thereof; and,
